OTTO CZARAN
INVENTOR

UNITED STATES PATENT OFFICE.

OTTO CZARAN, OF LONG ISLAND CITY, NEW YORK.

PROCESS FOR MAKING BELTING.

1,391,302.

Specification of Letters Patent. Patented Sept. 20, 1921.

Application filed January 28, 1919. Serial No. 273,649.

To all whom it may concern:

Be it known that OTTO CZARAN, subject of Austria-Hungary, and resident of Long Island City, in the county of Queens and State 5 of New York, has invented certain new and useful Improvements in Processes for Making Belting, of which the following is a specification.

This invention relates to belting and is 10 directed to a process for making belting for light machinery such as sewing machines and the like. The main object of my invention is to provide a process whereby belting of the character described may be made of 15 any desired cross-section in a continuous operation from a side of raw material such as leather, which results in a finished spliced belt of desired length.

A further object of this invention is to 20 provide a process for making belting of the character described which shall result in a belting that is completely finished, its surface being hardened, smoothed, and polished and the fibers thereof having been 25 lengthened by tension to prevent the finished belt from stretching unduly under strain and to overcome its elasticity whereby it tends to assume its original circular shape when fed from a disk of raw material. 30

Other objects and advantages will appear from the detailed description and the features of novelty will be particularly pointed out in the claims.

In the drawings accompanying this specification, I have shown a perfect form of apparatus for carrying out my newly improved process, and the process will be understood in connection with the apparatus 35 shown in these drawings and in which,

Figure 1 is a plan view of a machine embodying my invention and showing a table upon which are mounted the specific devices for performing the several operations 40 required in making the round belt and preferred means from driving said mechanism.

Fig. 2 is a side elevation of the structure illustrated in Fig. 1 and partly in longitudinal section.

Fig. 3 is a longitudinal view partly in section illustrating a construction for holding the disk of leather. It is rotated between a pair of rollers prior to being cut by the dividing knife and referred to in Fig. 1 by 45 line 3-3.

Fig. 4 is a cross-sectional view of the offset line 4-4 of Fig. 2.

Fig. 5 is a cross-sectional view on line 5-5 of Fig. 2 disclosing the removable spool in longitudinal section. 60

Fig. 6 is a detailed vertical sectional view on line 6-6 of Fig. 1 showing the means whereby the roller which is held to permit of lateral adjustment to provide for cutting the belt to a desired width. 65

The process will be best understood after a description has been given of the apparatus.

Referring in detail to the drawing, A indicates a table made preferably of cast iron 70 upon which are mounted rollers A', A', A', upon which is placed a disk of leather from which the belt is to be formed. B and B' indicate two rolls, the lower one B, of which is driven from the counter-shaft C through 75 the miter gearing C' and the edge of the leather disk is held between the said rolls and propelled thereby against the knife D which cuts it to the proper width, said width being determined by the position of the rolls 80 D', D'— as will hereinafter more fully appear. The upper roll B' is held in a frame B² which in turn is journaled on the pins B³, B³ which have their bearings in the outer frame B⁴ which in turn is held on 85 one end of the lever B⁵ and is pressed toward the roll by the spring B⁶ as will be readily understood. This construction permits the leather disk to be firmly held and propelled by the roller B and is made to conform to the variations in thickness of the leather and in case the leather is uneven or warped, to force the same into sure contact. 90 After the strip has been cut by the knife D it passes between two pairs of guide rolls, 95 E, E disposed in planes transverse to each other, to the cutting knife or trimmer F consisting of a conically formed tube, the small periphery of which is sharpened to provide a circular cutting edge to round the 100 square belt strip into circular cross-section.

The top rolls of the rolls E, E is also provided with a spring E' for tensioning them against the lower rolls. The belt then passes between the grooved rollers G, G which 105 are held closely together by spring G' located in the housing G² and is then led between the rollers H, H which are submerged in an oil bath I and thence between the rollers J, J and K, K and into the spool L 110

on which it is wound in successive layers and may be removed at this point if desired. Ordinarily, however, the spool L serves to pull the belt through, the latter being wound 5 several turns thereon and being driven through the shaft C and gearing C² the belt is drawn through by the spool L as it is being cut and shaped. The belt is then carried over the spool M and between the rollers m, m to the friction wheels, N, N and polishing wheels N⁴, N⁴ respectively. The contact surfaces of the polishing wheels are covered with raw hide or other suitable material to polish the surface of the round belt 10 by friction. The friction wheels, N, N are driven at a high speed and serve to smoothen and harden the surface of the belting. These sets of friction and polishing wheels are driven from the shaft O through the 15 gearing O', and the first set of polishing wheels is driven by means of the belt P and gearing P'. The wheels N, N are mounted on shafts N², N² respectively, supported in standards N³, N³ and the polishing wheels N⁴, N⁴ are held in a housing N'. The belt 20 then is passed successively between the rollers, R, R, S, S, T, T, and U, U and on to the spool driven through the miter gearing W' which is driven from the shaft O as will 25 be clear from the drawing. Clutch means X, X' are provided to connect and disconnect shafts C and O respectively from the main driving shaft Y.

The knife D is held in a bracket D² which 30 bracket also supports one of the rollers E, and said roller E and knife D are therefore adjustable with the bracket and held in adjusted relation by the screws D³ passing through the slot D⁴ formed in the 35 bracket.

The rollers D', D' and the roller E held by the bracket E' are adjustable to and from the strip of leather which is to be formed and the adjusting means consist of a plurality of wedge members d which clamp the 40 end of the journal d' firmly in any desired lateral adjustment.

Mounted on the table A is a bracket a which is adjustable longitudinally of the 45 table by reason of the slots a' and held in adjusted position by bolts b, b, indicates a drum having a continuous cam groove e' formed therein. Mounted on the bracket a is an arm f one end of which is pivoted on 50 the bracket as at g while the other end carries the guide pulleys K, K which are made to swing in the arc of a circle by the travel of the arm f in the groove e' by means of a stud i secured to the arm f and free to slide 55 in the slot f' formed in the arm f. The drum in turn is driven from the worm gear k which by reason of its slow transmission moves the drum slowly and in turn causes the pulley k to be swung back and forth to 60 wind the belt on the spool L in successive 65

layers, if desired. Ordinarily, however, the stud i is removed and the belt permitted after having a few turns taken on the spool to continue on to the spool M and thence to the polishing rolls. By a longitudinal adjustment of the bracket a the arc through which the pulley K, K, swings may be varied within limits to accommodate belts of different diameter to be carried back and forth the entire length of the spool. For 70 large variations the gearing may be changed as will be readily understood. When winding the belt after polishing on the removable spool L a similar drum n and like cam mechanism as just described is employed. 75 The guide rolls H, H, are carried on the lower end of a rod H' which is supported in the arm f and which is free to slide in a guide formed in the casting H² secured on the underside of the arm f and the belt can be placed under any required tension by means of the lever H³ and held in the adjusted position by means of the bracket H⁴ also carried by the arm f. As the arm f swings back and forth the rolls H, H also 80 swing back and forth through the bath. The rolls, J, J are slidably mounted on shafts extending across the bed A to the width substantially of the bath to permit the belt to remain in alignment when leaving the rolls 85 H, H and passing to the rolls K, K. I preferably use a bath of oil but may use any other suitable fluid.

The detailed construction of the removable spool is illustrated in Fig. 5, in which 90 L represents the spool and h, h, indicate flanges which carry pins h', h', to engage corresponding openings in the flanges of the spool. A bolt h² extends through an opening h³ formed in one of said flanges and 95 screws into the tapped socket h⁴ of the opposite flange. So that, by removing said bolt h² and sliding, the right hand flange h can be moved in the bearing h⁵ a distance corresponding to the length of twice the 100 length of the pins h', thus freeing the spool 105 as will be readily understood.

A brake is provided to prevent the reel M from unwinding except as the belt is 110 drawn to the polishing rolls. In the form shown this consists of a belt r, one end of which is held to a post s and the other end of which carries a weight, the friction of the belt preventing the reel from unwinding except as the belt is withdrawn therefrom.

The various steps in the process will now 115 be readily understood. As the raw material is fed in at the forward end of the machine by the rolls A' A' and the feed mechanism B, B², B³, the knife D cuts off a strip of 120 desired thickness regulated by the adjustment of the rolls D' as herein above described. The piece so cut is either square or rectangular in cross-section and is thence drawn through the trimmer F which gives 125 130

it a circular or other desired cross-section. The belting then passes through the oil bath I to soften the fibers. As it is being drawn through the bath it is stretched by the downward pressure between the rolls H, H, so that the fibers are stretched at the same time that they are being softened in the bath. The belting is further subjected to a longitudinal pulley throughout the whole operation, it being pulled through the various parts of the apparatus in succession under tension in the manner clearly hereinbefore explained. From the oil bath the belting passes between the friction rolls N, N. These are made to revolve at a high rate of speed and the heat developed by the friction helps harden the surface of the belting at the same time that it smoothens it. The belting then passes to the polishing wheels N⁴ where its surface is given a fine polish. From the polishing wheels it is wound on successive layers on a removable reel. Any desired lengths of finished belting may now be cut from the reel and the length formed into a complete continuous belt by splicing the ends thereof. This may be accomplished in any suitable manner and preferably by an apparatus constructed according to the disclosure in my co-pending application for patent Serial No. 273,647, filed January 29th, 1920.

Having thus described my invention, I claim:—

1. The process of making leather belting of desired cross-section consisting in cutting a strip of leather from the outer edge of a sheet of belting material, first forming said strip to the extreme width desired, then shaping it to desired cross-section, drawing it through a fluid bath under tension, thereby stretching the leather and causing the same to absorb a portion of said fluid, thence compressing said strip thereby smoothening and hardening the same, and then passing it between polishing wheels substantially as described.

2. The process of making leather belting of desired cross-section consisting in cutting a strip of leather from the outer edge of a sheet of belting material, first forming said strip to the extreme width desired, then shaping it to desired cross-section, drawing it through a fluid bath under tension, thereby stretching the leather and causing the same to absorb a portion of said fluid, thence compressing said strip thereby smoothening and hardening the same, and then passing it between polishing wheels substantially as described.

3. The process of making leather belting of desired cross-section consisting in cutting a strip of leather from the outer edge of a sheet of belting material, forming said strip to the extreme width desired, shaping it to desired cross-section, drawing it through a fluid bath under tension, compressing it in said fluid bath, passing it from said fluid bath between friction wheels to smoothen and harden the surface thereof by the heat developed, then passing it between polishing wheels, substantially as described.

4. The process of making leather belting of desired cross-section, consisting in cutting a strip of leather from the outer edge of a sheet of belting material inward toward the center thereof, forming said strip to the extreme width desired, shaping the same to desired cross-section, drawing it through a fluid bath and compressing it in said fluid bath and applying friction to said strip thereby smoothening and hardening the surface thereof by the heat developed and then polishing the strip substantially as described.

Signed at New York City, in the county of New York and State of New York, this 17th day of January, A. D. 1919.

OTTO CZARAN.

Witness:

FRANK M. ASHLEY.
